(57) **CLAIM**

The ornamental design for a set of decorative letters, as shown and described.

DESCRIPTION

FIG. 1 is a front, right and top perspective view of the letter A of a set of decorative letters showing my new design;

FIG. 2 is a rear, left and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a front, right and top perspective view of the letter B of a set of decorative letters showing my new design;

FIG. 10 is a rear, left and bottom perspective view thereof;

FIG. 11 is a front elevation view thereof;

FIG. 12 is a rear elevation view thereof;

FIG. 13 is a left side elevation view thereof;

FIG. 14 is a right side elevation view thereof;

FIG. 15 is a top plan view thereof;

FIG. 16 is a bottom plan view thereof;

FIG. 17 is a front, right and top perspective view of the letter D of a set of decorative letters showing my new design;

FIG. 18 is a rear, left and bottom perspective view thereof;

FIG. 19 is a front elevation view thereof;

FIG. 20 is a rear elevation view thereof;

FIG. 21 is a left side elevation view thereof;

FIG. 22 is a right side elevation view thereof;

FIG. 23 is a top plan view thereof;

FIG. 24 is a bottom plan view thereof;

FIG. 25 is a front, right and top perspective view of the letter E of a set of decorative letters showing my new design;

FIG. 26 is a rear, left and bottom perspective view thereof;

FIG. 27 is a front elevation view thereof;

FIG. 28 is a rear elevation view thereof;

FIG. 29 is a left side elevation view thereof;

FIG. 30 is a right side elevation view thereof;

FIG. 31 is a top plan view thereof;

FIG. 32 is a bottom plan view thereof;

FIG. 33 is a front, right and top perspective view of the letter K of a set of decorative letters showing my new design;

FIG. 34 is a rear, left and bottom perspective view thereof;

FIG. 35 is a front elevation view thereof;

FIG. 36 is a rear elevation view thereof;

FIG. 37 is a left side elevation view thereof;

FIG. 38 is a right side elevation view thereof;

FIG. 39 is a top plan view thereof;

FIG. 40 is a bottom plan view thereof;

(Continued)

FIG. 41 is a front, right and top perspective view of the letter M of a set of decorative letters showing my new design; FIG. 42 is a rear, left and bottom perspective view thereof; FIG. 43 is a front elevation view thereof; FIG. 44 is a rear elevation view thereof; FIG. 45 is a left side elevation view thereof; FIG. 46 is a right side elevation view thereof; FIG. 47 is a top plan view thereof; FIG. 48 is a bottom plan view thereof; FIG. 49 is a front, right and top perspective view of the Letter R of a set of decorative letters showing my new design; FIG. 50 is a rear, left and bottom perspective view thereof; FIG. 51 is a front elevation view thereof; FIG. 52 is a rear elevation view thereof; FIG. 53 is a left side elevation view thereof; FIG. 54 is a right side elevation view thereof; FIG. 55 is a top plan view thereof; FIG. 56 is a bottom plan view thereof; FIG. 57 is a front, right and top perspective view of the letter S of a set of decorative letters showing my new design; FIG. 58 is a rear, left and bottom perspective view thereof; FIG. 59 is a front elevation view thereof; FIG. 60 is a rear elevation view thereof; FIG. 61 is a left side elevation view thereof; FIG. 62 is a right side elevation view thereof; FIG. 63 is a top plan view thereof; and, FIG. 64 is a bottom plan view thereof. The broken lines in the figures depict portions of the set of decorative letters that form no part of the claimed design.
